BODY MASSAGING APPLIANCE

Louis B. Casagrande, Wauwatosa, and Paul H. Bonness, Milwaukee, Wis., assignors to Clum Manufacturing Company, Milwaukee, Wis., a corporation of Wisconsin

Application November 27, 1933, Serial No. 699,874

11 Claims. (Cl. 128—59)

This invention relates to improvements in body massaging appliances.

It is the primary object of the invention to provide a body massaging appliance which will duplicate more accurately than has heretofore been possible, the manipulation of the flesh by skilled human fingers.

More specifically stated, it is proposed to provide a device in which massage rollers, rotatably mounted on adjacent axes at an acute angle to each other, may be axially adjustable to and from the point of intersection of these axes, and are also axially yieldable automatically from said point of intersection in the course of manipulation of the flesh pressed therebetween.

Other objects of the invention pertain to the mechanical construction of the apparatus to provide a simple permanent assembly of the parts for the purposes stated.

In the drawing:

Figure 1 is a general perspective of apparatus embodying the invention.

Figure 2 is a view of the apparatus partially in end elevation and partially in section.

Figure 3 is a side elevation of the apparatus partially broken away to an axial section to show the connection of the handle therewith.

Figure 4 is an enlarged detail view taken in section in the plane indicated at 4—4 in Figure 2.

Figure 5 is a detail in perspective of the handle construction shown in Figure 3.

Like parts are identified by the same reference characters throughout the several views.

The tool head 6 preferably comprises a die-casting cored to provide bores at 7 having a flat side 8, as best shown in Fig. 4. These bores are intersected by kerfs 9 in which operate the knurled nuts 10 for the adjustment of spindles 11.

The spindles 11 are flattened at 12 to engage the flat surfaces 8 of the respective bores and are screw threaded to receive threaded connection with the nuts 10, whereby the spindles may be adjusted axially to and from the point at which the respective bores 7 would intersect if projected upwardly as viewed in Fig. 2. The engagement of the flat sides 12 of the spindles with the flat sides 8 of their respective bores, provides a splined connection which prevents the spindles from rotating and permits them to feed axially when the proper nut 10 is manipulated by the operator. The arrangement provided is such that the rollers 15 may be moved through a considerable range of adjustment between the full and dotted line positions shown in Fig. 2.

The rollers 15 are provided with bushings such

as that shown at 16 in Fig. 2 to turn freely upon the spindles 11. A split washer at 17 engaged about the spindle and abutted by the bushing 16 limits the extent to which the roller may move on the spindle toward the head 6. A small washer at 18 at the outer end of the spindle is disposed in a recess in the end of bushing 16 and provides an abutment for a compression spring 19 which exerts a thrust upon the bushing tending to maintain the roller normally at its extreme 10 limit of movement toward head 6.

In the casting of head 6, the head is provided with a boss at 20 having a recess 21 complementary to a lug 22 which is formed on the handle socket 23. A screw 24 has its head seated in the interior of the handle socket and passes through the lug 22 and boss 20 into the head 6 to anchor the socket rigidly and non-rotatably to the head. A wooden or any suitable handle 25 is engaged in the socket 23 and is held by a wood 20 screw 26 entering the handle through the socket from the under side as shown in Fig. 3.

The angle between the head 6 and the axis of handle 25 ensures that the implement will be held at the correct angle for proper application to 25 the body. The bores 7 in the head hold the spindles 11 at the proper acute angle with reference to each other. This angle is approximately 50 degrees. With the parts thus angularly related and supported, it will be found that when the 30 rollers 15 are passed over the body by a pushing, movement on handle 25, the rollers 15 will tend to draw the flesh of the body up in a roll or fold between the rollers with a definite massaging action upon the flesh thus engaged.

As the flesh is drawn between the rolls 15, there is a reaction on the rolls tending to move them outwardly upon their respective spindles 11 against the compression of the respective springs 19. This movement separates the rolls from 40 each other, due to the angularity of the spindles, and thereby prevents the massaging action from becoming too severe.

The rollers 15 are preferably made of some 45 relatively elastic material such as rubber, which is not only yieldable but is also capable of exerting a substantial frictional twist upon the flesh engaged thereby. Any materials may be used, however, within the purposes of the present invention, which is principally directed to the mechanical organization and the manually and automatically operable adjustments herein disclosed.

We claim:

1. In a flesh massaging tool, the combination 55

- with a pair of associated spindles, of rollers journaled to turn upon the axes of the respective spindles and reciprocable in the direction of the axes thereof and means to permit axial movement of the rollers when the flesh unduly accumulates between the rollers.
2. In a massaging tool, the combination with a pair of associated spindles, of roller applicators rotatably encircling the spindles and axially movable thereon, and means resiliently opposing the movement of the roller applicators axially of their respective spindles from predetermined positions thereon.
3. In a flesh massaging implement, the combination with a handle, of a pair of spindles diverging from each other, means connecting said spindles with said handle at an angle to each other, and roller applicators rotatably encircling the respective spindles for rotation thereon and for reciprocation to and from said handle whereby to permit axial movement of the rollers when the flesh unduly accumulates between the rollers.
4. In a massage implement, the combination with a handle, a pair of angularly related spindles having ends remote from the handle, and means for connecting said spindles with the handle in mutually divergent positions, of a pair of roller applicators mounted on the respective spindles for rotation thereon, and spring means yieldably urging the respective applicators from said ends of the spindles toward said handle, said applicators being automatically yieldable against the compression of said means away from said handle and from each other when in operation.
5. The combination with a pair of diverging spindles, of roller applicators journaled upon the spindles and rotatably and axially movable thereon, means limiting the movement of the respective applicators upon their spindles in a direction of approach toward each other, and means resiliently opposing the axial movement of the respective applicators in directions away from each other.
6. In a massage implement, the combination with a supporting spindle, of an applicator roller provided with a bushing guided upon said spindle for rotation and axial movement thereon, said bushing having a recess, a spring seated against said bushing at the end of said recess and provided with a seat upon said spindle, whereby said spring is housed within said recess and opposes axial movement of said applicator upon said spindle in one direction.
7. A massage implement comprising the combination with a supporting head and a pair of angularly divergent spindles, of means adjust-

ably mounting said spindles in said head for movement therein in the general direction of their respective axes, roller applicators carried by the spindles to partake of their axial adjustment respecting said head, said roller applicators being mounted on their respective spindles for axial movement with respect to the spindles, and springs interposed between said applicators and their respective spindles for opposing such relative axial movement.

8. A massage implement comprising the combination with a supporting head, of a pair of angularly divergent spindles, roller applicators rotatable and axially movable thereon, and means for individually opposing resiliently the movement of said applicators in an axial direction away from said head.

9. A massage implement comprising the combination with a supporting head, of a pair of angularly divergent spindles individually splined in said head, nuts axially confined with respect to said head and rotatably engaged in threaded connection with the respective spindles for their individual axial adjustment, said nuts being exposed at the sides of said head for manipulation and roller applicators rotatably mounted on the respective spindles to partake of such adjustment.

10. A massage implement comprising the combination with a supporting head, of a pair of spindles connected with said head, means for axially adjusting at least one of said spindles respecting said head, roller applicators mounted on the respective spindles for rotation and axial movement thereon, means defining the limit of axial movement of said applicators toward said head, and means for resiliently opposing the yielding of said applicators from said limit of movement.

11. A massage implement comprising the combination with a supporting head and a pair of spindles angularly divergent from said head and provided with means for their individual axial adjustment respecting said head, of roller applicators mounted on the respective spindles for rotative and axial movement thereon, limiting means on each spindle defining the limit of applicator movement toward the head, abutment means spaced outwardly on each spindle from said limiting means, and compression springs housed within the respective applicators and confined between portions of said applicators and the abutment means of their respective spindles, whereby yieldably to oppose the movement of said applicators away from said head.
